REMOVABLE TOP CONTAINER ADAPTED FOR MOUNTING ON A ROAD VEHICLE

Charles R. Gretz, 4 Pomona Circle,
Valdosta, Ga. 31601

Filed May 14, 1968, Ser. No. 11,918

Term of patent 14 years

Int. Cl. D12—14, 99

U.S. Cl. D14—27

FIG.1

FIG. 1 is a left front perspective view of a removable top container adapted for mounting on a road vehicle showing my new design;

FIG. 2 is a left side elevational view thereof;

FIG. 3 is a front elevational view thereof;

FIG. 4 is a rear elevational view thereof;

FIG. 5 is a partial cross-sectional view thereof taken along line 5—5 of FIG. 1; and

FIG. 6 is a left rear perspective view thereof with the top partially removed therefrom.

I claim:

The ornamental design for a removable top container

adapted for mounting on a road vehicle, substantially as shown.
